METHOD FOR THE CORRECTION OF MALFUNCTIONING MUSCLES OF MASTICATION

John Hinton Shackelford, Baltimore, Md.

Application November 30, 1953, Serial No. 394,955

2 Claims. (Cl. 128—68)

The present invention relates to a method and articulator for the correction of malfunctioning muscles of mastication and it consists in the combinations, constructions and arrangements of parts together with the method herein described and claimed.

Generally the present invention relates to a method and a device utilized to carry out such method for the treatment of malposition of the mandible due to the loss of posterior teeth in cases in which a few natural teeth remain. The method is based upon a series of clinical observations made by the inventor with relation to the functional behavior of the muscles of mastication, which observations have led the inventor herein to the conclusion that muscle length in the human body is predetermined by the genes and influenced by diet and exercise and that, therefore, there is an optimal distance over which a muscle will function with maximum efficiency. If a muscle is forced to function continually over a distance greatly in excess of optimal distance, a gradually mounting tension in the muscle fibres will result and, if a muscle is caused to function continually over a distance considerably less than optimal, a gradually mounting tension in the muscle fibres will likewise result. If a muscle is functioning over a distance less than was established as optimal by the genetic determinations, it would have to bunch and tense itself before it could contract sufficiently to reach its work load. Therefore, if such a muscle were stretched toward a distance slightly less than or approximating that over which it functioned before the loss of natural posterior teeth there should be a lessening of tension, an improvement in muscle coordination, a reduction of traumatic mastication and an improved sense of well-being in the patient. Therefore, one of the objects of the present invention is the treatment of patients whose mandibular position has shifted with prosthetic appliances which have caused the muscles to stretch and the angles of the mandible to be displaced downwardly, thereby withdrawing the condyle heads from their traumatic position in the glenoid fossae. When the muscles begin to stretch, the mandible rotates with the angles as the central area in the rotation. Thus, as the condyle heads are withdrawn from their malposition in the glenoid fossae, the symphosis of the mandible and the anterior teeth rotate upwardly slightly distal to the upper anterior teeth. As adjustments of prosthetic appliances are made to permit lateral excursive motions, the mandible can be permitted to move slightly forwardly until a desirable relationship is attained between the upper and lower anterior teeth provided there has not been too great anterior displacement of the upper teeth. This method of repositioning the mandible in cases where a few natural teeth remain is made possible by the fact that the muscles improve in their functional efficiency and coordination when stretched toward their optimal functioning distance, tension in the muscles decreasing, and their rate of fatigue is extended over a longer interval. The inventor has noted that patients treated by the pres-

2

ent method have an interval of discomfort of approximately three to five days during the initial stretching of the muscles; that, in the average case, the mandible movement is satisfactorily completed in from six weeks to two months; and that an improvement in the coordination of the adjacent sets of muscles such as the facial muscles, the muscles of the floor of the mouth, the tongue, and those involved in positioning and moving the head is noted by the end of the third month.

5 10 It is accordingly an object of the invention to provide a method of correcting the malfunctioning of the muscles of mastication.

Another object of the invention is to provide a novel articulator for accomplishing the first-mentioned object.

15 Other and further objects of the invention will become apparent from a reading of the following specification taken in conjunction with the drawings, in which:

Figure 1 is a side elevational view of an articulator forming a part of the invention,

20 Figure 2 is a top plan view thereof,

Figure 3 is a bottom plan view thereof,

Figure 4 is a vertical sectional view of the device illustrated in Figures 1 to 3, inclusive,

25 Figure 5 is a sectional view taken substantially along line 5—5 of Figure 1,

Figure 6 is an end elevational view taken in the direction of the arrow "A" in Figure 1,

30 Figure 7 is a fragmentary side elevational view illustrating the principal portions of a human skull which come into consideration in carrying out the present invention, and

35 Figures 8 to 10, inclusive, are schematic views illustrating the method of correction of malfunctioning muscles of mastication which method forms a part of the present invention.

Referring more particularly to the drawings, there is shown therein, in Figures 1 to 6, inclusive, an articulator comprising a horizontally extending substantially rectangular base plate 10 having a reduced rectangular portion 11 at the inner end thereof from which there extends centrally and upwardly a pin 12. There is also provided a vertically extending substantially square hollow housing generally indicated at 13 having an inner wall 14, an outer wall 15 and a pair of side walls 16. A vertically extending block 17 is snugly and slidably mounted in the housing 13 and is provided in its lower end with a socket 18 for snugly and slidably receiving therein the upper end of the pin 12.

50 The outer wall 15 is provided with thickened portions 19, 20 and 21 in which there is threadably mounted set screws 22, 23 and 24, respectively. The screw 22 is adapted to bear against the side of the pin 12 while the screws 23 and 24 are adapted to bear against the adjacent side of the block 17. Centrally affixed in the upper end of the block 17 and extending upwardly therefrom is a pin 25 which is exteriorly threaded for the reception thereon of a nut 26.

A horizontally extending substantially rectangular upper plate 27 of relatively narrower width than the plate 10 is provided with a substantially square reduced portion 28 at its inner end and the upper end of the block 17 is provided with a substantially square socket 29 for the reception therein of the reduced portion 28. An upwardly extending transverse shoulder 30 is provided upon the plate 10 and is adapted to abut against the outer face of the lower portion of the wall 15. The underside of the plate 27 is provided with a transversely extending shoulder 31 which is adapted to abut against the upper edge of the wall 15 and it will be seen that the lower edge of the wall 15 is cut away sufficiently to permit the horizontal pas-

sage therethrough of the reduced portion 11 of the plate 10.

Referring now to Figure 7, it will be seen that there is therein shown a crude representation of portions of the human skull in which 32 designates the auditory canal, and in which the interarticular fibrocartilage or meniscus is shown at 33. Bearing against the meniscus 33 is the mandibular condyle 34 of the inferior maxillary 35, the superior maxillary being illustrated at 36. 37 indicates the posterior border of the fossa while 38 indicates the articular eminence. The upper teeth are generally indicated at 39 while the lower teeth are generally indicated at 40.

In Figures 8 to 10, inclusive, the upper teeth 39, the lower teeth 40 together with the lower jaw and mandibular condyle are graphically illustrated to progressively show the functioning of the present method, the corrected lower teeth being indicated at 40a in Figures 9 and 10 while the lower teeth, prior to their correction by this method, are indicated at 40 in Figure 8. In all three figures, 8 to 10, inclusive, there is indicated at X the pivotal point of the lower jaw prior to its correction and at X' the desired pivotal point for such lower jaw in order to bring about the objects of the present invention.

In carrying out the present invention plaster casts of conventional character are affixed to the upper side of the plate 10 and lower side of the plate 27 in the identical relationship to each other that they have in their position in a patient's mouth. The articulator is preferably formed of aluminum or other light metal to make it sufficiently light in weight to avoid the straining of the hands of technicians working with the same and it will be apparent that the plates 10 and 27 so designed that lateral motion with respect to each other is impossible due to the close fitting of the reduced portions 11 and 28 with their three associated elements. When the casts have been mounted upon the plates 10 and 27 the "bite" of such casts may be opened a predetermined distance by first loosening the screws 22, 23 and 24 to thereby permit vertical movement of the block 17. The inner face of the block 17, indicated at 42, is preferably provided with millimeter calibrations so that the distance the casts are moved apart may be readily determined after which the screws 22, 23 and 24 are again tightened to maintain such distance. It will be apparent that the bite, although opened, will remain always in horizontal relation.

The amount of the opening between the two casts aforementioned will be determined by previous observations of the patient to determine the distance it is desired to move the pivotal point of the mandibular condile 34, that is to say the distance between X and X'. The partial dentures and, in some cases, a partial lower and

full upper denture are then built up by the operator to open the bite relationship between the two casts while maintaining their horizontal relationship with one another. This is illustrated graphically at 40a in Figures 9 and 10 which are, of course, greatly exaggerated in order to illustrate the principle employed herein. When the dentures have been so built up, it will be apparent that initially the rearward ends of the upper tooth assembly will meet with the rearward ends of the lower tooth assembly as indicated in Figure 9 thus forcing the muscles such as, for example, the masseter muscles, to distend a greater distance to allow full closure of such teeth as indicated in Figure 10. This action will bring the pivotal point of the mandibular condile 34 from that indicated at X to the corrected position indicated at X', thus lessening the tension in such muscles and eventually adding to the general well being of the patient and, in many cases, preventing loss of hearing due to the occlusion of the auditory canal 32 by upward and rearward pressure of the mandibular condile 34 against the auditory meatus of the canal 32.

While but one form of the invention has been shown and described herein, it will be readily apparent to those skilled in the art that many minor modifications may be made without departing from the spirit of the invention or the scope of the appended claims.

What is claimed is:

1. The method of correction of malposition of the mandible due to loss of certain posterior teeth of a person having dentures for said lost teeth comprising first, fabricating plaster casts of the upper and lower teeth and dentures of the person needing such correction; next, moving said casts apart to a predetermined spaced parallel relation with respect to each other; and, finally, building up said dentures to open the bite relationship between said casts while maintaining their parallel relationship to each other.

2. The method of correction of malposition of the mandible due to loss of posterior teeth of a person having dentures for said lost teeth comprising first, determining the distance between the position of the condiles of the malposed mandible and their proper positions; and next, building up said dentures an amount necessary to provide fulcruming contact points whereby said condile heads are forced to move to correct positions when the upper and lower teeth and dentures are brought together.
